UNITED STATES PATENT OFFICE.

WILLIAM ERASTUS WILLIAMS, OF WILMETTE, ILLINOIS, ASSIGNOR TO AMERICAN STEEL FOUNDRIES, OF CHICAGO, ILLINOIS, A CORPORATION OF NEW JERSEY.

DISK-WHEEL HUB FASTENING.

Application filed December 23, 1922. Serial No. 608,770.

To all whom it may concern:

Be it known that I, WILLIAM ERASTUS WILLIAMS, a citizen of the United States, a resident of Wilmette, in the county of Cook and State of Illinois, have invented a new and useful Improvement in Disk-Wheel Hub Fastenings, of which the following is a specification.

The object of my invention is to furnish a very cheap and secure fastening for the disk of a disk wheel to its hub.

Reference will be had to the accompanying drawings in which Figure 1 is a front elevation of the main portion of my preferred form of the wheel.

Figure 2 is a side sectional view.

Figure 3 is a rear elevation of a portion of a disk surrounding the hub of the disk form shown in Figures 1 and 2.

Figure 4 is a front elevation of the hub alone.

Figure 5 is a rear elevation of the hub clamping flange 12.

Figures 3, 4, and 5 are special to the structure shown in Figures 1 and 2.

Figure 6 is a front elevation of a modified form of the wheel the difference between the structures of Figure 1 and Figure 6 relating to co-acting hub-clamping features.

Figure 7 is a vertical sectional elevation of the wheel shown in Figure 6.

Figure 8 is a sectional view on line 8—8 of Figure 7.

Figure 9 is a perspective view of a portion of the disk alone as used in Figures 1 and 2.

Figure 10 is a perspective view of the disk as shown in Figures 6 and 7.

In the drawing 1 indicates the hub of an automobile wheel here shown as the rear hub, 2 indicates the ordinary brake drum, 3 a rim of the quick detachable type adapted to carry a pneumatic tire, 4 the integral hub flange as used in Figures 1 and 2, and 5 indicates that portion of the brake drum in Figures 1 and 2 that is connected to the integral hub flange 4.

The wheel shown in Figures 1 and 2 is what is known as a convex type of disk while that shown in Figures 6 and 7 is for a concave type of disk, however either type of disk may be used with either fastening.

In Figures 1 and 2 the integral hub flange 4 is provided with a flange having a ruffled or fluted tapering seat 7 adapted to fit the

ruffled inclined projecting flange 8 on the hub aperture of the disk 9. The disk 9 is secured to the rim 3 through the medium of a horizontal flange 10 and rivets 11, but may be seated as desired in any suitable manner in connection with the rim 3.

The ruffled flange 8 is held in engagement with the seat 7 of the hub flange 6 by means of a clamping ring 12 having an inclined ruffled marginal flange 13 which has a smooth concentric edge 14. The flange 12 is provided with nut seats or bosses 15 upon which are clamped the nuts 16 of the stud bolts 17 passing through the holes 18 of the ring 12 and through holes in the hub flange 4 and flange 5 of the brake drum and are secured in the rear by nuts 19. A flange 20 on the bolts 17 permits the bolts to stay in place and clamp the brake drum 2 to the flange 4 of the hub at intervals when the nuts 16 are removed for the purpose of demounting the disk from the hub in tire changes as is well understood.

The ruffled flange on the disk seated in the hub as described makes a secure fastening for the parts and a cheap one to make.

In Figures 6 and 7 the integral hub flange is indicated by 21 to which the web 22 of the brake drum is secured by a series of bolts 23.

This hub flange 21 is provided with a ruffled outwardly extending flange 24 provided with reinforcing pads 25 through which there passes the bolts 23.

The disk which forms the web of the wheel in Figures 6, 7, and 8 is provided with an inclined ruffled flange 26 which is seated on the ruffled flange 24 of the hub. The hub clamping flange in the structure shown in Figures 6 and 7 is indicated by 27 and is seated on the hub barrel 1 with a small flange 28 and this flange 27 has a ruffled flange 29 which is seated on the ruffled flange 26 of the disk. The bolts 23 are provided with shoulders 30 that allow the nuts 31 to clamp the brake drum and integral flange 21 of the hub together. Demounting nuts 32 also on the bolts 23 serve to clamp in a demountable fashion clamping flange 27 and thus to secure demountable fastening for the disk and hub.

The disk which forms the web of the wheel extends from the ruffled hub flange 26 through the region 33 into the swell 34 and thence into the concave portion 35 which is

merged forwardly into the felloe face 36 and from this turned over into an inclined flange 37 and this turned into the marginal flange 38 and thus through the flanges 37 and 38

5 the disk is connected to the rim 3.

A series of clamping bolts 39 having nuts 40 serve to secure a member 41 in such manner that its margin 42 clamps the quick detachable rim 3 to its seat 37, 38 on the disk.

10 In Figures 9 and 10 the disks shown in Figures 1 and 2 and Figures 6 and 7 are associated together the difference being that the concave disk may be said to have a convex ruffled flange and the convex disk to have 15 concave ruffled flange. In either case the method of holding the disk to the hub is through the medium of a ruffled flange on the disk around the hub barrel connection.

The ruffled flange on the disk makes a 20 cheap and yet a very secure fastening for a disk of any thickness when seated on a hub flange by any suitable means of holding the disk and the hub together.

What I claim is:—

25 1. In a device of the class described, a disk forming the web of the wheel and united to the rim by a flange turned over on the margin of the disk on to which the rim is seated and a flange turned over in ruffled form around the hub aperture in combination with a hub having a surface adapted to seat on the ruffled flange of the disk and a clamping flange bearing against the disk and adapted to press the same into engagement with the hub in a manner that the ruffled flange of the disk is made to fit snugly into the ruffled seat on the hub.

30 2. In a wheel of the class described, a disk forming the web of the wheel and provided 40 with an aperture around the hub zone and said aperture having a ruffled flange turned out from the metal of the disk in an inclined position in combination with the hub having an inclined bearing surface adapted to engage the said ruffled flange of the said disk a clamping ring mounted over the hub barrel and adapted to clamp the disk in relation

to the hub in direction parallel with the axis of the wheel, by means of a series of bolts passing through the clamping flange and secured into the hub. 50

3. In a device of the class described, a disk forming the web of the wheel and provided with a ruffled flanged aperture around the hub connection, in combination with externally convex, internally concave connections of the hub members adapted to fit, respectively, the internal and external faces of the ruffled flange on the disk. 55

4. In a device of the class described, a 60 disk having a ruffled flange turned around a hub aperture, a hub having the flange approximating the shape of the ruffled flange on the disk and a clamping flange for clamping the said hub and disk together by means 65 of a series of bolts passing through the hub flange and the clamping flange.

5. In a device of the class described, a 70 disk having a ruffled flange around a hub aperture, a hub provided with a flange approximating the shape of the ruffled flange on the disk, a clamping flange for clamping the disk to the hub flange and having a bearing surface adapted to engage the ruffled flange of the disk and a series of bolts for clamping the clamping flange and hub flange together.

6. In a device of the class described, a disk having a ruffled flange around a hub aperture, a hub with a flange having a surface approximating the ruffled flange on the disk, a clamping flange adapted to clamp the disk to the hub flange through the medium of bolts passing through the hub flange and clamping flange and said clamping flange having a wedge fit in contact with the said disk.

Signed at Chicago, in the county of Cook and State of Illinois, this 21st day of December, 1922.

WILLIAM ERASTUS WILLIAMS.
